RIGID FRAME EXTRUSION

Theophile L. De Zinne, 1337 SW. 14th St.,
Miami, Fla. 33145

Filed Jan. 28, 1975, Ser. No. 544,931

Term of patent 14 years

Int. Cl. D25—01

U.S. Cl. D25—75

FIG.1

FIG.2

FIG. 1 is an inner perspective view of a rigid frame extrusion, showing my new design.

FIG. 2 is a perspective outer view thereof.

The frame extrusion, made from metal or plastic material, is adapted to retain glass or other panels therein.

I claim:

The ornamental design for a rigid frame extrusion, as shown and described.
